Primary Examiner — Ian Simmons*Assistant Examiner* — Harold Blackwell, II*(74) Attorney, Agent, or Firm* — Dicke, Billig & Czaja, PLLC(57) **CLAIM**

The ornamental design for a LED light bulb, as shown and described.

DESCRIPTION

FIG. 1 is a front, top perspective view of the LED light bulb of the present design;

FIG. 2 is a front plan view of the LED light bulb of FIG. 1;

FIG. 3 is a back plan view of the LED light bulb of FIG. 1;

FIG. 4 is a left side view of the LED light bulb of FIG. 1;

FIG. 5 is a right side view of the LED light bulb of FIG. 1;

FIG. 6 is a top plan view of the LED light bulb of FIG. 1; and,

FIG. 7 is a bottom plan view of the LED light bulb of FIG. 1.
